UNITED STATES PATENT OFFICE.

CHARLES F. WILSON, OF BROOKLYN, NEW YORK.

AUTOMATIC TENDER FOR TROLLEY-OPERATING ROPES.

SPECIFICATION forming part of Letters Patent No. 597,159, dated January 11, 1898.

Application filed October 1, 1896. Serial No. 607,611. (No model.)

To all whom it may concern:

Be it known that I, CHARLES F. WILSON, of Brooklyn, in the county of Kings and State of New York, have invented a new and useful Improvement in Automatic Tenders for Trolley-Operating Ropes, of which the following is a specification.

My invention relates to an improvement in automatic tenders for trolley-operating ropes with the object in view of simplifying and rendering more reliable the device for which United States Letters Patent No. 563,531 were granted to me on the 7th day of July, 1896.

A practical embodiment of my invention is represented in the accompanying drawings, in which—

Figure 1 is a view in side elevation of the device as it appears when attached to the dashboard of a car-platform in use, portions of the car-roof, line-wire, trolley-arm, and dashboard being shown. Fig. 2 is a view of the device, in rear elevation, detached from the car. Fig. 3 is a top plan view of the same, showing the manner of attaching it to the dashboard. Fig. 4 is a front view of the same with the front or outer cap-plate removed to show the actuating-spring. Fig. 5 is a view in transverse section, showing the cap-plate in position; and Fig. 6 is a sectional view taken in the plane of line 6 6 of Fig. 5 and transverse to the axis of the winding-reel and showing the locking and releasing dogs in front elevation.

The operating mechanism is supported in a cylindrical casing A in the form of a thin hoop or band fastened at its rear edge to the periphery of a thicker disk B, which may be formed integral therewith, and having at its back a slot b for the reception of a flat bar C, fixed to the face of the dashboard D of the car.

It is desirable to provide means for attaching the automatic tender to and detaching it from the dashboard with great facility as the car shifts its direction of travel along the track, and to this end I provide the thin bar C, extending horizontally along the face of the dashboard D and spaced therefrom just sufficient to permit the back plate B to be slid over its free end, utilizing for this purpose the same bolt-holes in the dashboard which commonly receive the bolts d d' for securing

the operating-shaft E in its position. When slid in position, as shown in Figs. 1, 3, and 4, it may be temporarily secured upon its support by means of a link c, adapted to drop into an open slot c' in the upper edge of the fixed support C, the said link c having a chain connection c² with the casing of the tender. 55

The front of the back plate B is provided with an annular flange b', having on its inner face, at intervals thereon, inwardly-projecting teeth b², with which the locking and releasing dogs engage, as will hereinafter more particularly appear. 60

The back plate B is further provided with a forwardly-extending stub-axle b³, on which is mounted the rope-retaining reel and which I preferably construct as follows: The hub of the reel has a contracted portion F, which fits loosely on the stub-axle b³, at that end of the axle in proximity to the back plate B, and a portion F', of greater diameter than the portion F, which forms a cylindrical housing for the reel-actuating spring G and at the same 75 time a bearing for the chain H, which is connected with the lower end of the trolley-operating rope h. The inner flange or side rail is denoted by f and the outer flange or side by f'. The former is riveted to that portion 80 of the hub of the reel which connects the portion F' of greater diameter with the portion F of lesser diameter, and the side f' is riveted to a flange f², which projects in a radial direction from the front edge of the portion 85 F' of the hub. By means of this structure I am enabled to form the flanges of the reel of thin sheet metal and secure them in position on the hub, while the hub itself may be formed of a heavier material to serve the 90 double purpose of journaling the reel on the axle and at the same time forming a housing for the spring, so as to leave the several parts in position where they may be readily examined and removed. 95

The spring G has one end connected to a stub-axle and the opposite end to the interior of the portion F of the reel-hub, and the reel is secured in its position on the stub-axle by means of a screw g and into the end of the stub-axle b³, the periphery of the cap-plate g' having a bearing against the front or outer edge of the portion F' of the reel-hub. 100

The reel itself is located within the cylindrical casing A, and the rope or chain which leads from the hub of the reel passes through a tubular guide *a*, which is fixed to and surrounds an opening in the casing A, thereby preventing the chain *H* from escaping from its position between the flanges of the reel no matter how suddenly the slack in the trolley-operating rope *h* may take place.

10 I have shown and described a chain *H* in connection with the operating reel-hub, as it in practice works in many respects better than to continue the rope itself through the guide *a* and onto the reel-hub; but I wish it 15 to be understood that the rope itself may be continued, if preferred, and take the place of the chain *H*.

On the rear of the inner side of the flange *f* of the reel the locking and releasing dogs 20 *I* *I'* are pivoted—in the present instance on studs *i* *i'*, fixed to the flange *f*. The dogs *I* *I'* are connected to operate in unison by means of a link *K*, which connects the operating end of one dog with the tail of the opposite dog.

25 To determine the freedom with which the two dogs shall be thrown outwardly under the centrifugal force due to the rotary movement of the reel, I provide a bar or spring *k*, fixed at one end to the tail of the dog *I*—in 30 the present instance by means of a slot in the dog—and a set-screw *k'*, engaged with the dog in position to impinge against the end of the spring within the slot, the said spring having its free end engaged with a stop-pin *l* on the disk *L*, which may be locked in different rotary adjustments by means of a set-screw *l'*, so as to increase or decrease the 35 pressure of the spring from the stop *l* and thereby retard or relieve the movement of 40 the dogs.

To obviate any liability of breaking or disarranging the reel-actuating spring *G*—as, for example, by winding it in the reverse direction from that in which it should be wound—

45 I attach it to the axle *b*³ in the following manner: In the axle *b*³ there is formed a V-shaped notch *b*⁴, (see Fig. 4,) and the inner end of the spring *G* is provided with a hook *g*², which when the spring *G* is wound in the proper direction catches in the notch *b*⁴, as shown in Fig. 4, and holds the end of the spring against slipping around the axle; but if the spring should be unintentionally or intentionally wound in the opposite direction the hook *g*² 50 would free itself from the notch *b*⁴ and slip around the axle and thereby relieve the strain and prevent the spring from breaking.

For convenience in lubricating the reel I provide a socket *b*⁵, extending from the back

of the plate *B* toward the front end of the axle *b*³ and connected by one or more lateral passages *b*⁶ with the exterior of the axle within the portion *F* of the hub.

In operation as the trolley-arm *M* vibrates during its travel the spring *G* will rotate the reel in the direction to take up any slack which may occur in the the rope *h*, and under ordinary circumstances the movement of the reel will be sufficiently slow to prevent the dogs *I* *I'* from being thrown out into engagement with the teeth on the back of the casing; but if the trolley at any time escape from the main wire and the trolley-arm *M* be thereby left free to fly upwardly its forward movement would be promptly checked by the outward throw of the dogs *I* *I'* into engagement with the teeth on the back of the casing.

To remove the tender from one end of the car to the other requires simply the removal of the link *c* from the supporting-arm *C* and the sliding of the tender-casing off and over the end of the support *C* and again sliding it onto the similar support at the opposite end of the car. The supports provided for the tender occupy positions on the dashboards 85 which do not to any considerable extent interfere with traffic, and they may be applied to the dashboards without requiring the cutting of additional bolt-holes.

What I claim is—

1. The automatic tender, comprising a suitable support, a spring-actuated reel mounted on the support, a dog carried by the reel and mounted to swing outwardly into engagement with the support and a dog-regulating spring 95 consisting of a bar or plate spring carried by the dog and means for adjusting the free end of the spring in a lateral direction to increase or diminish its retarding effect upon the dog, substantially as set forth.

2. The trolley-tender, comprising a reel for receiving the trolley-arm-operating rope, means for regulating the rotary movement of the reel and a coil-spring for actuating the reel, the said spring having one of its ends 105 fixed to the hub of the reel and its opposite end engaged with the axle from which the reel rotates, the connection between the spring and the axle being such that the end will be held fast when the spring is drawn in one direction and set free when the spring is drawn in the opposite direction, substantially as set forth.

CHARLES F. WILSON.
